PARASITICIDE

Jacob M. Schaffer and Frank W. Tilley,
Washington, D. C.No Drawing. Application September 9, 1929,
Serial No. 391,520

2 Claims. (Cl. 167—31)

(Granted under the act of March 3, 1883, as
amended April 30, 1928; 370 O. G. 757)

This application is made under the act approved April 30, 1928, and the invention herein described, if patented, may be manufactured and used by or for the Government for governmental purposes without payment to us of any royalty thereon.

We hereby dedicate the invention herein described to the free use of the public, to take effect upon the granting of a patent to us.

10 This invention relates to new compositions of matter having for their object the utilization of the parasiticidal properties of orthophenylphenol.

15 The new compositions comprise orthophenylphenol in the free or combined state, and a suitable vehicle therefor, and may be used in the solid state, as a dust or cake, or in the liquid state, as an emulsion or solution.

20 We have found that orthophenylphenol possesses marked parasiticidal properties. Its solubility in water is so low, however, that these properties have in the past failed to be observed. We have found that orthophenylphenol may be rendered more soluble in water by suitable admixture with other substances. In such compositions of matter it has many valuable properties: it is markedly parasiticidal; it has marked antiseptic properties; it is practical and convenient to use; it has no objectionable odor; it may be made non-irritating; it has a low toxicity to higher animals; it has many applications.

25 A solid preparation may be made in many ways, one of which is by mixing orthophenylphenol with hydrated lime in the form of a white dry powder. This mixture may be applied as a parasiticidal white wash. Another useful form is the combination of orthophenylphenol or its alkaline salts with coconut oil soap in the form of a solid or liquid soap using orthophenylphenol one part and coconut oil soap two to eight parts. We prefer to use soaps made from cocoanut oil fatty acids, although soaps made from other materials may also be used. Orthophenylphenol and

its alkaline salts when mixed with soap is non-irritating to animals, depending on the proportions of the several ingredients for example, coconut oil soap four parts, orthophenylphenol one part. A solution of orthophenylphenol may be made in an organic solvent, as 30% glycerine, in which form it may be used directly on the body surfaces of higher animals without irritation, or dissolved in animal, vegetable or mineral oil in which form it may conveniently be used for internal administration to higher animals. Orthophenylphenol may be mixed with alkaline substances or solutions to obtain readily parasiticidal concentrations when diluted with water.

30 It is to be understood that while we have hereinbefore given several specific examples of the forms and combinations in which orthophenylphenol and its alkaline salts may be used as parasiticides, we do not limit ourselves to such forms and combinations, but desire it to be understood that orthophenylphenol and its alkaline salts may be used in many other combinations, too numerous to enumerate, all of which combinations, even though not specifically described, will be obvious to those skilled in the art to which this invention relates.

35 As examples of parasites which have been destroyed by dilutions of 0.2 per cent and less of orthophenylphenol in above mentioned compositions of matter may be mentioned, bacillus typhosus, staphylococcus aureus, bacillus tuberculosis, lice on hogs, fleas on dogs, etc.

We claim:

1. A parasiticide consisting of orthophenylphenol and coconut oil soap as a solvent for the orthophenylphenol.

2. A parasiticide comprising orthophenylphenol and a solvent therefor comprising coconut oil soap in an aqueous vehicle.

40 JACOB M. SCHAFFER.
FRANK W. TILLEY.
